UNITED STATES PATENT OFFICE.

WILLIAM D. McCORMACK, OF NASHVILLE, TENNESSEE.

ATTACHMENT FOR AIRCRAFT TO RENDER SAME INVISIBLE.

1,297,882.

Specification of Letters Patent. Patented Mar. 18, 1919.

Application filed August 20, 1917. Serial No. 187,303.

To all whom it may concern:

Be it known that I, WILLIAM D. McCORMACK, a citizen of the United States, residing at Nashville, in the county of Davidson, State of Tennessee, have invented certain new and useful Improvements in Attachments for Aircraft to Render Same Invisible; and I do hereby declare the following to be a full, clear, and exact description of the invention, such as will enable others skilled in the art to which it appertains to make and use the same.

My present invention relates to improvements in attachments for air-craft to render the same invisible. It consists in applying a detachable sheathing made of light flexible material, which may be readily applied and removed as desired, and it may be varied to suit pending conditions of the weather. Thus in clear weather, with blue sky, I provide a flexible sheathing of substantially sky blue color, while in cloudy or foggy weather, I provide a flexible sheathing of gray color.

This sheathing may be made of any suitable material, preferably translucent material, such as celluloid or other suitable material, which is made the desired color, and which is silvered or bronzed on the face thereof next the air-craft so that the light passing through this translucent material may be reflected outward, and will have the same color as the sky or the clouds, as the case may be.

This material is intended to be applied to only the more prominent parts of the aircraft, such as on an aeroplane, the wings, body portion, the tail, diving rudders, struts etc., while with a dirigible the more prominent parts would be similarly covered, especially those parts exposed to view from below.

Instead of sheathing the entire aeroplane as described, the wings, rudders and part of the tail of the aeroplane may be made of transparent material which may be reinforced with wire if desired, and the stanchions, engine room, cock pit and other parts of the aeroplane may be sheathed as hereinafter described.

My invention will be more clearly understood after reference to the accompanying drawings, in which:

Figure 1 shows a side elevation of an aeroplane of well known type, showing the sheathing applied thereto.

Fig. 2 is a view on a larger scale of a

portion of one of the wings with the sheathing applied thereto.

Fig. 3 shows a view on a larger scale of a pair of the fastening ribs used to connect the sheathing to the aeroplane.

Fig. 4 shows a section on the line 4—4 of Fig. 1, looking in the direction of the arrows, and shows the mode of attaching the sheathing to the body of the aeroplane.

Fig. 5 shows one of the struts detached from the machine with the sheathing applied thereto.

Fig. 6 shows a section along the line 6—6 of Fig. 5, looking down, the parts being shown on a larger scale.

Fig. 7 is a detail showing one of the brackets for holding the straps in place on the body of the machine.

Fig. 8 shows on an exaggerated scale one of the translucent sheets having a silvered face.

Fig. 9 is a perspective view of a portion of a wing made of transparent material.

Fig. 10 shows a cross section through a pair of the fastening straps shown in Fig. 9.

Fig. 11 shows a U clamp for use on the edge of the wing, and of the rudders, and

Fig. 12 shows an L clamp for use at the corners of the body of the aeroplane.

In practice it is only necessary to apply the sheathing to the wings A, A', the body portion B, struts C, steering rudder D, and diving rudder E, as the other parts of the machine would ordinarily be invisible at any appreciable distance, but the sheathing may be applied to all parts of the machine except the propellers, if desired.

The sheathing consists preferably of a sheet of material 1, such as celluloid or other suitable material more or less translucent, and made the desired color so as to render the same substantially invisible.

The inner face of this sheet next the part to be screened, is silvered as at 2, see Fig. 8.

These sheets may be conveniently applied to the wings A by the metal straps 3 hinged together as at 4 at one end, and fastened together at the other end as at 5, by bolts and nuts, as shown in Figs. 2 and 3. These straps may be further secured to the wings by means of bolts and nuts 6, as shown in Fig. 2.

In order to secure the sheathing to the body of the machine I preferably provide flat sheets, as shown at 1 in Figs. 1 and 4, which sheets may be held in place by the

metal straps 7, hinged together as at 8 and fastened as at 9, see Fig. 4.

In order to prevent these straps from sliding longitudinally on the body of the aeroplane, I may provide guide brackets 10, as shown in Fig. 7, which have guide lugs 11, and bolted to the body of the machine by bolts or rivets passing through the holes 12.

- The steering rudder is similarly provided
 10 with sheathing plates 1, fastened to it by means of the straps 13 similar to those already described with relation to the wings. In the same way the diving rudders E may have the sheathing applied thereto by means
 15 of the straps 14. The struts C may have the sheathing applied thereto by means of straps 16, hinged together as at 17, and fastened at the opposite side, as at 18, see Figs. 5 and 6.
 20 All of these straps 3, 7, 13, 14 and 16 are preferably rounded exteriorly, as shown in Fig. 3, so as to diminish the resistance to the air.

These sheets should be of standard shapes
 25 to fit the various types of machines, and the securing metal straps should also be made of standard sizes and arranged so as to be quickly assembled or removed from the machine, so that different colored sheathing
 30 may be applied when desired.

It is not necessary to have the sheathing all blue or all gray, as indicated, it may be mottled; that is, it may be partly blue or partly gray, or for night work the sheathing
 35 may be made black or dark brown, if desired, so as not to be visible.

The straps may be made of aluminum or galvanized steel, or suitable material, and may be colored or nickelized to match the
 40 sheathing used.

I have found in practice that the light will pass through the translucent face of the material and will be reflected back, causing the blue sheathed aircraft to be practically
 45 invisible in a blue sky, and a gray sheathed craft to be practically invisible in a gray sky.

Instead of sheathing the entire air-craft with the invisible material, a larger part of
 50 the aeroplane may be made of transparent material such, for instance, as clear celluloid, or other desired material, reinforced by small wire netting, if desired, as shown at 23 in Fig. 9. In Fig. 9 I have shown a
 55 portion of a wing made of such material 19 with metal fastening straps 3 and interior strips 20, which inclose the clear sheet and also the U clamp 21 and secure the two together.

When the straps 7 pass over the angular 60 corners of the body of the aeroplane, L clamps 22, see Fig. 12, may be interposed between the straps 7 and the angular corners of the aeroplane body.

While I have illustrated the sheathing as 65 applied to a bi-plane, it will be obvious that it may be applied also to monoplanes, tri-planes, hydroaeroplanes, or to dirigibles.

I do not mean to limit myself to any particular mode of attaching the sheathing to 70 the air-craft, as this might be done in a great variety of ways without departing from the spirit of my invention.

Having thus described my invention, what I claim and desire to secure by Letters Pat- 75 ent of the United States is:

1. A sheathing for air-craft comprising a series of strips of flexible translucent material colored to suit weather conditions, with means for detachably connecting said 80 sheathing to the air-craft, substantially as and for the purpose described.

2. A sheathing for air-craft comprising a series of strips of flexible translucent material colored to suit weather conditions, 85 each strip being provided with a silvered backing adjacent to the part of the air-craft to be screened, with means for detachably connecting said sheathing to the air-craft, substantially as and for the purpose described.

3. A sheathing for air-craft comprising a series of strips of flexible translucent material colored to suit weather conditions, with a series of metal straps hinged together in 95 pairs for detachably connecting said sheathing to the air-craft, substantially as and for the purpose described.

4. A sheathing for air-craft comprising a series of strips of flexible translucent material colored to suit weather conditions, each strip being provided with a silvered backing adjacent to the part of the air-craft to be screened, with a series of metal straps hinged together in pairs for detachably connecting said sheathing to the air-craft, substantially as and for the purpose described.

5. An aeroplane having the wings, rudders and part of the body portion thereof made of transparent material and the stan- 110 chions and remainder of the body portion sheathed with strips of flexible translucent material colored to suit weather conditions, substantially as described.

In testimony whereof, I affix my signa- 115 ture.

WILLIAM D. McCORMACK.
